DESIGN FOR A BRACKET SIGN

Hyman C. Hammer, Chicago, Ill.

Application December 5, 1938, Serial No. 81,576

Term of patent 3½ years

To all whom it may concern:

Be it known that I, Hyman C. Hammer, a citizen of the United States and resident of Chicago, in the county of Cook and State of Illinois, have invented a new, original, and ornamental Design for a Bracket Sign, of which the following is a specification, reference being had to the accompanying drawings forming a part thereof.

Fig. 1 is a front elevational view of the bracket sign, embodying my invention,

Fig. 2 is a top plan view of the same.
Fig. 3 is a bottom plan view of the same.
Fig. 4 is a side elevation of a view of the same.
Fig. 5 is a rear elevation of a view of the same.
I claim:
The ornamental design for a bracket sign, substantially as shown.

HYMAN C. HAMMER.
